UNITED STATES PATENT OFFICE.

CHARLES GREY HILL, OF ARNOT HILL, ENGLAND.

DESIGN FOR AN EDGING OR TRIMMING.

SPECIFICATION forming part of Design No. 21,129, dated October 27, 1891.

Application filed August 15, 1891. Serial No. 402,760. Term of patent 14 years.

To all whom it may concern:

Be it known that I, CHARLES GREY HILL, a subject of the Queen of Great Britain, residing at Arnot Hill, in the county of Nottingham, England, have invented and produced a new and original Design for Edgings or Trimmings, of which the following is a specification, reference being had to the accompanying drawings, forming part thereof.

Figures 1 and 2 are views of opposite sides of the edging.

The edging is formed of two bands of crimped fabric *a* and *b*, either of the same or different colors, bent into equal or unequal zigzags, which are laid one upon the other

and caused to adhere, each angle of each zigzag being placed between two angles of the other zigzag.

The leading feature of my design for an edging or trimming consists in two bands of crimped fabric formed into zigzags, the angles of each zigzag lying between two angles of the other zigzag.

What I claim is—

The design for an edging or trimming substantially such as herein shown and described.

CHARLES GREY HILL.
